UNITED STATES PATENT OFFICE.

JOSEPH GRIEN, OF CHICAGO, ILLINOIS, ASSIGNOR TO HAMILTON-ROSS FACTORIES, INC., A CORPORATION OF ILLINOIS.

DESIGN FOR A BRACKET FOR ELECTRIC LAMPS.

Application filed June 23, 1927. Serial No. 22,533. Term of patent 7 years.

To all whom it may concern:

Be it known that I, JOSEPH GRIEN, a citizen of the United States, residing at Chicago, Illinois, have invented a new, original, and ornamental Design for a Bracket for Electric Lamps, of which the following is a specification, reference being had to the accompanying drawing, forming a part hereof, in which—

Fig. 1 is a front view showing my new design;

Fig. 2 is an edge view.

I claim:

The ornamental design for a bracket for electric lamps, as shown.

JOSEPH GRIEN.
